Primary Examiner — Manpreet S Matharu*Assistant Examiner* — Mojtaba Tehrani(74) *Attorney, Agent, or Firm* — Wolf, Greenfield & Sacks, P.C.(57) **CLAIM**

The ornamental design for a recreational flotation device, as shown and described.

DESCRIPTION

FIG. 1 is a perspective view of a recreational flotation device in accordance with my new design.

FIG. 2. is a top plan view of the recreational flotation device, the bottom plan view being identical thereto.

FIG. 3 is an elevational view of the right side of the recreational flotation device of FIG. 1, the elevational view of the left side being a mirror image thereof.

FIG. 4 an elevational view of the lower end of the recreational flotation device of FIG. 1; and,

FIG. 5 is an elevational view of the upper end side of the recreational flotation device of FIG. 1.
